UNITED STATES PATENT OFFICE.

VIRGIL CROCKETT, OF DEXTER, MAINE.

DOUBLE-SEAMING MACHINE.

SPECIFICATION forming part of Letters Patent No. 372,896, dated November 8, 1887.

Application filed August 17, 1887. Serial No. 247,173. (No model.)

To all whom it may concern:

Be it known that I, VIRGIL CROCKETT, of Dexter, in the county of Penobscot and State of Maine, have invented a new and Improved 5 Double-Seaming Machine, of which the following is a full, clear, and exact description.

My invention relates to an improvement in machines for double-seaming tinware, and has for its object to provide a machine simple in 10 construction and effective in operation, whereby a perfect seam may be made in an expeditious and efficient manner.

The invention consists in the construction 15 and operation of the several parts, as will be hereinafter fully set forth, and pointed out in the claims.

Reference is to be had to the accompanying drawings, forming a part of this specification, in which similar letters of reference indicate 20 corresponding parts in all the figures.

Figure 1 is an elevation of one side of the machine with the parts in operative position. Fig. 2 is an elevation of the opposite side of the machine, parts being broken away; and 25 Fig. 3 is a plan view.

In carrying out the invention, the frame consists of a standard, A, having an arm, B, integral with the top and extending out at right angles thereto; and the said standard is also 30 provided upon the side with an outwardly-projecting horizontal bracket, a, upon the outer end of which bracket, beneath the arm B, a lug, a', is cast, provided with a horizontal aperture, and at the opposite end of the 35 bracket a similar apertured lug, a'', is formed, partly upon the bracket and partly in the standard, the apertures in the lugs being in alignment.

In the apertures of the lugs a' and a'' a horizontal shaft, C, is journaled, adapted to extend outward beyond each lug, and provided upon the inner end with a reduced left-hand threaded portion, c, carrying a nut, c', and at the extreme right-hand threaded end, c'', outside the nut c', with a disk, D, having a central aperture tapped with a right-hand thread, the purpose of the nut c' being to regulate the distance the disk is to be screwed upon the shaft. The outer end of the shaft C, or the end 45 projecting beyond the lug a'', is provided at its extremity with a crank-arm, d, whereby the

shaft is rotated, and between said lug and crank the shaft is further provided with an annular recess or groove, d'. The end of the standard-arm B is bifurcated, and each member is apertured in vertical alignment. Between the said members a nut, D', is placed, having the front end transversely slotted to intersect the central aperture, and provided with a set-screw, e, passing through the nut and slot at right angles to the latter. 55

Through the apertures in the bifurcated end of the arm B and through the threaded aperture in the nut D', a screw-shaft, D'', is projected, provided with a flat thread, the said 60 screw-shaft being vertical and at right angles to the rotary shaft C. The upper end of the screw-shaft is made rectangular for the application of a wrench, whereby the said shaft is made to travel up or down through the nut D'. 70 Near the lower end a collar, e', is formed, below which collar the shaft is made to receive an apertured head, E, provided with an integral hub, E', and the head and shaft are held in connection by a set-screw, e'', passed through the hub 75 into a groove formed in and around the shaft, as shown in dotted lines in Fig. 2. The head E is provided with an annular peripheral recess, f, upon the under or engaging face, the walls of which recess are adapted when the machine 80 is in operation to bear upon the periphery and outer face of the disk D. A lever, H, is fulcrumed to the rear edge of the standard A. The lower end of the lever is concaved and enters the groove d'. Above the fulcrum the 85 said lever is curved, so that the upper end will incline to the front and reciprocate upon the side of the standard A opposite to that carrying the projection a. The lever H has a metal yoke, h, attached to the forward edge of the 90 upper end, in which a friction-roller, k, pivoted at one end of a horizontal lever, K, is adapted to travel. The said lever K is fulcrumed upon the arm B near its end, and the inner end of the lever is pivoted on a pin, k', integral with the nut D'. The lever K is reciprocated from an ordinary foot-treadle through the medium of a connecting-rod, M. 95

In operation the disk D and the head E are simultaneously brought together or moved 100 apart by the manipulation of the lever K, which lever acts directly upon the shaft car-

trying the head through the nut D' , which is secured to the shaft by the set-screw e , and indirectly upon the disk through the curved lever H . Various sizes of disks and heads 5 may be employed to suit different classes of work. When the seam has been partially formed, interlocked, and placed upon the disk, and the head is brought in contact with the incomplete seam, the two parts of the seam, by 10 turning the crank-arm d , are united as closely as desired, according to the pressure brought to bear upon the two formers.

It will be observed that the machine is easily 15 and quickly set to different size disks, and that it does not necessitate an experienced hand to manipulate it; also, that the heads may be quickly changed, the machine placed 20 for operation upon a table by securing the base of the standard by screws or clamps, and, further, that no spring or other delicate mechanism liable to frequent disarrangement or breakage is employed.

Having thus fully described my invention, I claim as new and desire to secure by Letters 25 Patent—

1. The combination, with the standard A and attached arm B , a shaft, C , journaled horizontally in said standard, a threaded shaft, D^2 , held to slide in said arm at a right angle to 30 the shaft C , and an interiorly-threaded nut, D' , adapted to receive the shaft D^2 , of a disk, D , detachably attached to the shaft C , and a head, E , provided with an annular peripheral recess, F , detachably secured to the said shaft 35 D^2 at right angles to the disk D , and means for simultaneously bringing the said head and disk in contact, substantially as shown and described.

2. The combination, with the standard A , 40 the integral arm B , having a bifurcated end, a nut, D' , held within said bifurcation, a horizontal shaft, C , journaled in said standard, provided with a thread at one end and an adjusting-sleeve, C' , upon said thread and a

crank at the other, and a vertical threaded 45 shaft held to slide in said arm and secured in said nut, of a detachable disk attached to said shaft C , a head, E , provided with an annular peripheral recess, F , detachably secured to said threaded shaft, and means for simultaneously 50 bringing said head and disk in contact, substantially as herein specified.

3. The combination, with the standard A , 55 the arm B , having a bifurcated end, a split nut, D' , held in said bifurcation, a horizontal shaft, C , journaled in said standard, provided with a crank, d , annular groove d' , and thread e , and the threaded vertical shaft D^2 , held by 60 said nut and sliding in said arm, of the disk D , detachably secured to the shaft C , the recessed head E , detachably attached to the shaft D^2 , the curved lever H , resting in the groove 65 of the shaft C , the horizontal lever K , connected with said lever H and nut D' , and means for manipulating said lever K , substantially as herein specified.

4. The combination, with the standard A , 70 the arm B , having a bifurcated end, a split nut, D' , held in said bifurcation, a horizontal shaft, C , journaled in said standard, provided with a crank, d , annular groove d' , and thread e , and the threaded vertical shaft D^2 , held by 75 said nut and sliding in said arm, of the disk D , detachably secured to said shaft C , the recessed head E , detachably attached to the shaft D^2 , 80 the curved lever H , engaging the groove in the shaft C , provided at its upper end with a yoke, h , a horizontal lever, K , provided at one end with a friction-roller, k , engaging said yoke and attached to said nut D' at the other end, and means for manipulating said lever K , substantially as shown and described, and for the purposes herein set forth.

VIRGIL CROCKETT.
